[57] CLAIM

The ornamental design for a welder's gauntlet, as shown and described.

DESCRIPTION

FIG. 1 is a top plan view of a welder's gauntlet showing my new design;

FIG. 2 is a bottom plan view thereof;

FIG. 3 is a right side elevational view thereof;

FIG. 4 is a left side elevational view thereof;

FIG. 5 is a front elevational view thereof; and,

FIG. 6 is a rear elevational view thereof.

The surface shading patterns shown in all views are understood to repeat throughout the indicated areas.
